200,774

COMBINED RADIATION SHIELD AND WIRE SUPPORT FOR A SPARK PLUG

Russell G. Livingston, 5919 W. 74th St.,
Los Angeles 45, Calif.

Filed May 23, 1963, Ser. No. 75,036

Term of patent 14 years

(Cl. D26—1)

FIG. 1.

FIG. 2.

FIG. 3.

FIG. 4.

FIG. 1 is a perspective view of a combined radiation shield and wire support for a spark plug, showing my new design;

FIG. 2 is a side elevation thereof showing a typical position to which the wire support may be bent;

FIG. 3 is a front elevation thereof; and

FIG. 4 is a bottom plan view thereof.

I claim:

The ornamental design for a combined radiation shield and wire support for a spark plug, as shown.
